C. L. DAVIS

SPINE TREATING APPARATUS

Filed Jan. 25, 1924

Inventor

Charles L. Davis

By

Fetherstonhaugh & Co

Attorney

UNITED STATES PATENT OFFICE.

CHARLES LESTER DAVIS, OF SANTA BARBARA, CALIFORNIA.

SPINE-TREATING APPARATUS.

Application filed January 25, 1924. Serial No. 688,586.

To all whom it may concern:

Be it known that CHARLES L. DAVIS, a citizen of the United States, and resident of Santa Barbara, county of Santa Barbara, 5 and State of California, has invented certain new and useful Improvements in Spine-Treating Apparatus, of which the following is a specification.

This invention relates to spine stretching 10 or exercising apparatus and the object is to provide an apparatus of this nature which is portable and embodies means enabling the apparatus to be set up for operation at any desired point, thus dispensing with permanent fixtures and pulley arrangements of 15 the type heretofore employed.

A further object of the invention is to provide an improved head harness which may be quickly applied in position and is 20 self-adjustable to fit various sizes of heads and to equalize the pressure between the front chin strap and the back head strap.

A still further object of the invention is to provide an improved portable supporting bracket over which an operating cable attached to the head harness is adapted to pass.

Other objects of the invention, as well as the details of construction, combination and 30 arrangement of parts constituting the preferred embodiment disclosed herein will be more readily understood from the following description and accompanying drawings; in which,

35 Fig. 1 is a view of my device as it will appear in use.

Fig. 2 is a fragmentary perspective view 40 of the device showing the construction of the head harness and the manner in which the same is attached to the operating cable.

Fig. 3 is a detailed sectional view on the line 3—3 of Fig. 1.

As herein disclosed, the invention contemplates the provision of a head harness embodying rings 5 and 6 carrying an endless strap 7 which is passed through said rings to provide a front chin engaging portion 7' and a back head engaging portion 7'', these two portions being stitched together at the point 8 to anchor the strap to the ring 5, while permitting free sliding movement of the strap through the ring 6. Due to its slippage through the ring 6, the strap 7 is rendered self-adjusting to fit va-

rious types of heads and to equalize the 55 pressure between the front and back engaging portions 7' and 7''.

The rings 5 and 6 are secured to the ends of a connecting strap 9 carrying slidably a further ring 10 to which is anchored one 60 end of a cable 11. This cable is trained for sliding movement over a suitable bracket 12 and is equipped at its free end with a handle member 13 so that, as shown in Fig. 1, the wearer of the device can exert the required tension on the head harness by pulling downwardly on the handle.

As disclosed herein, the bracket 12 consists of a vertical portion 13' provided at its upper end with a rearward projection 14 70 and at its lower end with a forward projection 15. The projection 14 is preferably in the form of a horizontally extending block screwed or otherwise secured to the back of the portion 13' and adapted to rest on a head casing 16 or other suitable support. Preferably the projection 14 is provided with anti-slipping devices 17 to hold the same in a fixed position on the support 16. 75

The lower or front projection 15 is in the form of a half-sheave screwed or otherwise secured to the front of the vertical portion 13' and presenting a semi-circular groove 18 for the reception of the cable 11. However, in order to hold the cable against lateral displacements from the groove 18, I provide a latch member 19 mounted at its upper end on a pivot 20 and having its lower end grooved to conform to the contour of the cable and to enable the said end of the latch member to closely approach the grooved surface of the sheave 15 to prevent side movement of the cable, as shown to advantage in Fig. 3.

By reason of the particular construction of the bracket 12 it will be evident that my device as a whole is of a portable nature capable of being conveniently set up at any designated point where there is a support equivalent to the element 16 disclosed herein.

A further advantage of the construction set forth herein is the self-adjusting feature of the head harness and the ease with which said harness can be applied or removed.

The particular manner in which the strap 7 is connected to the rings 5 and 6 and through the strap 9 to the cable 11 is of

advantage in that it provides for the requisite equalization of pressure between the front and back strap portions 7' and 7".

In the foregoing, I have disclosed what I now consider to be a preferred embodiment of my invention but it will be understood that any desired modifications may be made within the scope of the appended claim.

10. What I claim is:

An apparatus of the class described, com-

prising a head harness, a bracket member presenting a semi-circular groove a cable slideable in said groove and attached at one end to said harness and a latch member pivoted to said bracket and normally disposed to hold the cable against escape from said groove.

15 In testimony whereof I hereunto affix my signature.

CHARLES LESTER DAVIS.
